UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 13,986, dated June 19, 1883.

Application filed May 4, 1883. Term of patent 3½ years.

To all whom it may concern:

Be it known that I, PAUL PIGNOT, of Yonkers, Westchester county, and State of New York, have invented a new and original Design for Carpets, of which the following is a specification.

The accompanying photograph illustrates my new design for carpets.

This invention relates to a new design for carpets, oil-cloths, and analogous fabrics; and it consists of the new ornamentation of parts, hereinafter more fully pointed out.

The letter *a* in the accompanying photograph

represents a small pond, around which are clustered plants *b* and flowers *d*. Farther back are to be seen the trunks of trees *A* and their foliage. The space *e* between the trees is shaded off, so as to give the effect of a distance of view between the foliage.

I claim—

The design for carpets, consisting of the figures *a*, *b*, *d*, *c*, and *A*, substantially as shown.

PAUL PIGNOT.
